ABSTRACT OF THE DISCLOSURE

A brief is formed with a crotch portion constructed of material which is stretchable in a longitudinal direction to provide a supporting pouch for the body of a male wearer. The body portion of the garment is formed directly from a tubular section of material with a separate crotch portion being sewn thereto. Elongate binding strips for the leg openings of the brief are folded along their lengths to produce inner and outer layers which are themselves folded to produce reinforcing layers. An elastic strip is disposed between the reinforcing layers of the inner layer and captured between a double stitching arrangement used to join the binding strip to the leg openings.

FIELD OF THE INVENTION

The present invention relates to men's and boy's briefs and more particularly to an improved brief and to a material guide or former used in the construction of the improved brief.

BACKGROUND OF THE INVENTION

A particularly vexing problem concerning men's and boy's undergarments of the type known as briefs is that of providing a satisfactory crotch portion and particularly to providing a satisfactory support pouch for the body of the wearer.

One objection to conventional briefs is that they are oftentimes too tight in the crotch area. Conventional briefs generally do not provide "give" in the crotch area such that the shape of the crotch may stretch to conform to the body of the wearer. Further, garment shrinkage will often result in a reduction of the length of the crotch portion of the brief with an attendant increase in tightness. There have been numerous attempts at providing improved crotch support, including the provision of a dart or extra seam in the crotch to enlarge the supporting area thereof. Briefs so constructed have not been found to be entirely satisfactory in that they do not always provide effective support. Further, the effectiveness of the support provided may vary from wearer to wearer because the supporting area is of a particular predetermined shape and thus may not be completely suitable for each individual. The problem of providing satisfactory support in the crotch area relates to a more general problem of wearer comfort. In general an approach that depends upon additional seams is unlikely to be entirely satisfactory because of the discomfort caused by the additional seams. Further, the addition of seams will add to the overall expense of the garment because of the increased labor costs due to increased handling and sewing. The addition of seams will also add to the problem of shrinkage in that in general the greater the number of seams the greater the amount of shrinkage likely to occur.

Another problem encountered in garments of this type is that of the separation of the elastic strip or whatever other elasticizing medium is used for the garment leg openings from the binding strip and garment proper so

2

that the naked strip is exposed. Where this elastic medium is exposed, as through destruction of the mounting threads therefor by abrasion, the discomfort occasioned thereby often cause a wearer to discard the garment well before the end of the natural life of the garment.

SUMMARY OF THE INVENTION

In accordance with the present invention there is provided a man's brief wherein the lower or crotch portion thereof is stretchable in a longitudinal direction to form a pouch portion. In accordance with a presently preferred embodiment the brief is of two piece rib-knit construction, and includes a crotch portion in which the ribbing thereof extends transversely in a direction perpendicular to the longitudinally extending ribbing of a trunk or body portion of the brief. With this ribbing arrangement the crotch portion is relatively free to stretch in a longitudinal direction to form a supporting pouch. In accordance with a presently preferred embodiment of the invention the body portion of the brief is formed directly from a tubular section of material and the crotch portion is formed from a separate cut-out section and thus a minimum number of seams is required. The body and crotch portions are formed and dimensioned such that longitudinal stretch is confined to the crotch area.

In accordance with a further feature of the present invention there is provided an improved elasticized binding arrangement for the leg openings of the brief. Longitudinal stretch in the crotch portion of the brief is particularly desirable at the central portion of the crotch and less desirable at the portions adjacent the leg openings. Thus it may be desired to provide elasticized binding for the leg openings to ensure a snug fit in these areas. In accordance with the present invention a thin strip of elastic is disposed between the layers produced by folding one edge of the binding strip along a longitudinal fold line before sewing. With this arrangement a compartment is formed for the elastic strip which has been found to effectively combat the tendency with repeated wearing and washing of the elastic strip to come out of the binding. The elastic is not sewed to the binding or the garment proper and thus elasticized thread constructed of a material such as "Spandex" is not necessary.

In accordance with a further feature of the invention a material guide used in sewing of the binding to the garment proper is provided which delivers the elastic strip and the binding material to be sewn with the required folds made in the binding material and with the elastic strip suitably positioned between the layers of one of the folds.

Other features and advantages of the present invention will become apparent upon consideration of the following description of the invention taken with the accompanying drawings in which:

FIG. 1 is a front view of a brief constructed in accordance with the invention;

FIG. 2 is an inside front view of a first embodiment of the invention;

FIG. 3 is a representation of a blank of material used in constructing the trunk portion of the brief of FIG. 2;

FIG. 4 is a representation of a blank of material used in constructing the crotch portion of the brief of FIG. 2;

FIG. 5 is an inside front view of a second embodiment of the invention;

FIG. 6 is a representation of a folded blank of material used in constructing the trunk portion of the brief of FIG. 5;

FIG. 7 is a crotch view of the brief of FIG. 1;

FIG. 8 is an enlarged sectional view of the leg binding for the briefs of FIGS. 1-7 including the needles for sewing the binding to the garment proper;

FIG. 9 is a perspective view of a fabric guide or folder used in preparing the binding of FIG. 8 showing the binding material being fed therethrough; and

FIG. 10 is a view taken generally along line A—A of FIG. 9 with the material removed for purposes of clarity.

Referring to FIGS. 1, 2 and 7 of the drawings there is shown a first embodiment of a man's brief generally denoted B constructed in accordance with the present invention. Brief B generally comprises a body portion 10 and a crotch portion 12. An elastic waistband 14 encircles the trunk opening of body portion 10 while leg bindings 16 encircle the leg openings for the brief. The construction of leg bindings 16 is shown in FIG. 8 and is discussed in some detail hereinbelow.

The construction of brief B will be better appreciated upon consideration of FIGS. 3 and 4 in which there is shown, respectively, a blank for forming the body portion 10 and a blank for forming crotch portion 12 of the garment. Referring to FIG. 3, the body or trunk portion 10 of the garment is constructed from tubular blank of material T cut to form a front portion 18 and a rear portion 20. As shown, the lower edge of front portion 18 is of concave semicircular shape. The lower edge of rear portion 20 extends below the lower edge of front portion 18 and is cut straight across as shown. The tubular blank of material is taken directly from the knitter and thus the brief is effectively knit to size.

Referring to FIG. 4, crotch portion 12 is constructed from a flat blank of material C one end of which is generally V-shaped and the other end of which is cut straight across.

The finished garment of FIGS. 1, 2 and 7 is constructed by sewing the end of crotch blank C including the straight edge to lower edge of the rear portion 20 of body blank T. The stitching may be covered by a finishing strip 22 as indicated in FIG. 7. The V-shaped end of crotch blank C is sewed to the front portion 18 of body blank T. The locations at which blank C is sewed to blank T may best be seen in FIGS. 1 and 2. A finishing strip 24 is sewed to blank T along the concave semi-circular lower edge thereof as is indicated in FIG. 2 while one edge of the V-shaped portion of crotch blank C is sewed to the body blank T as indicated by stitching 26. A finishing strip 28 shown in FIG. 1 covers stitching 26. The other edge of the V-shaped portion of crotch blank C is left unsewn and forms the fly opening for the garment. A finishing strip 30 is sewn to the fly-forming edge of crotch blank C (see FIG. 1). Thus the fly passage extends between crotch portion 12 and the lower semi-circular edge of body portion 10 to which finishing strip 24 is sewn and out between body portion 10 and the finished edge 30 of crotch portion 12.

In accordance with an important feature of the present invention the ribbing or wales of the fabric from which crotch blank C is constructed extends in a transverse direction, i.e., parallel to the width of blank C, as indicated in FIG. 1, whereby longitudinal stretching of crotch portion 12 is permitted. It will be understood that the terms transverse and longitudinal are referenced to the body of the wearer, the term "longitudinal" meaning generally parallel to the length of the torso. As can be seen in FIGS. 1 and 2 and in comparing FIGS. 3 and 4 the ribbing of the crotch portion 12 extends transversely while the ribbing of the body portion 10 extends longitudinally. Because rib-knit material permits stretch in a direction perpendicular to the direction in which the ribbing extends but is relatively inelastic in the parallel direction, this construction permits longitudinal stretching of crotch portion 12 to form a pouch. This construction contrasts with and, in fact, is directly opposite to that of the prior art wherein the ribbing is vertical and thus stretch in the crotch area is horizontal. Longitudinal or vertical stretch is critically important in men's and boy's briefs because, as stated, room is

provided for forming a pouch for the wearer and thus tightness of the garment in the crotch area is substantially eliminated. Further, a pouch so formed is adapted to the body of the individual wearer and thus a kind of "custom" fit is provided.

An important feature of the particular embodiment of the invention shown in FIGS. 1-4 is that a minimum number of seams is required. As stated hereinbefore a reduction in seams generally increases wearer's comfort, decreases manufacturing costs and decreases shrinkage. Regarding shrinkage it is noted that with the construction of the invention the usual reduction in length of the garment and attendant increase in tightness in the crotch area accompanied by shrinkage in the body portion is combatted by the ability of the garment to stretch in the crotch area.

Referring to FIGS. 5 and 6, an alternate method of constructing the brief of the invention is illustrated. FIG. 5 is similar to FIG. 2 and like elements are given the same numbers with primes attached. In FIG. 6 a blank T' used in forming the body or trunk portion of the brief B' of FIG. 5 is shown. Blank T' is cut out from a tubular section of material 32, indicated in phantom in FIG. 6, which is flattened out to form two longitudinal folded edges. One of these edges denoted 34 is retained when blank T' is cut out and thus a double layer is formed. The blank T' is unfolded and the outer edges 36 (one of which may be seen in FIG. 6) are sewn together to produce a section of garment similar to body blank T of FIG. 3. The blanks T and T' differ physically only in the presence of seam 38 formed by the sewing together of the outer edges 36 of blank T. The crotch blank used to form the crotch portion 12' of brief B' may be exactly the same as that used in forming crotch portion 12. This blank and blank T' are sewn together in the same way as described hereinabove in connection with blank C and blank T and the finished brief B' is physically indistinguishable from brief B' apart from seam 38. Both briefs B and B' are characterized in that the ribbing of the crotch portions thereof extends transversely to provide longitudinal stretch. A further important common feature of the brief constructions B and B' is that the longitudinal stretch thereof is confined to the crotch area. Longitudinal stretch elsewhere in the garment is undesirable because such stretch will destroy the shape and fit of the garment. As may perhaps best be seen in FIGS. 4 and 7 crotch portion 12 and rear portion 20 are formed and dimensioned such that the rearward extent of the straight portion of crotch portion 12 is limited and thus that the seat of the garment will stretch transversely.

Referring to FIG. 8, a detail view is shown of the manner of attachment of a leg binding 40 to a portion of the garment proper denoted 42. Binding 40 is constructed from an elongate strip of fabric material which folded along a longitudinal fold line denoted 44 to produce outer and inner layers 40a and 40b. Portion 42 of the garment extends between layers 40a, 40b to a position adjacent the longitudinal fold line 44. Layer 40a is folded inwardly and downwardly along a longitudinal fold line 46 to form a first reinforcement layer 40c and layer 40b is folded inwardly and upwardly along a longitudinal fold line 48 to form a further reinforcement layer 40d. Leg binding 40 further includes an elongate strip of elastic 50 positioned between layers 40b and 40d as shown and extending parallel to the edges of layers 40c and 40d. Elastic strip 50 is captured between the threads forming a double stitch 52 as can be seen in FIG. 8 by the positioning of strip 50 in relationship to sewing needles 54. As stated hereinbefore the "compartment" formed by layers 40b and 40d and the double stitch 52 has been found to be markedly advantageous in preventing separation or exposure of the elastic strip 50. Strip 50 is not sewn to the binding 40 but is, as stated, captured between the double stitch 52 and thus it is unnecessary

sary that the thread used itself be elastic. It is noted that where, as in certain prior art constructions, an elastic strip is sewn directly to the garment it is preferable that the thread used be capable of stretching so that pulling out of the stitching is combatted. It will be understood that although the binding strip arrangement of the invention is particularly suited to use in briefs of the type described this arrangement may have utility in any elasticized garment opening. For example, the binding strip arrangement of the invention may be utilized in a garment which includes leg portions which extend to the mid-thigh area of the wearer, the arrangement providing an elasticized opening in this area.

It will be understood by those skilled in the art that the embodiments of the invention shown and described herein are subject to modification without departing from the scope and spirit of the invention. Accordingly, it should be understood that the invention is not limited by the embodiments shown and described, but rather is defined by the subjoined claims.

We claim:

1. A brief for a male wearer comprising a directionally stretchable trunk portion constructed of rib-knit material and having leg openings and an enlarged waist opening for receiving the trunk of a wearer, said trunk portion being substantially non-stretchable in a longitudinal direction parallel to the longitudinal extent of the body of the wearer and being stretchable in a transverse direction perpendicular to said longitudinal direction, and a directionally stretchable crotch portion constructed of rib-knit material for supporting the lower body of the wearer, said crotch portion being substantially non-stretchable in said transverse direction and being stretchable in said longitudinal direction to form a pouch for the lower body of the wearer, said trunk portion comprising a trunk member comprising a generally tubular section of material having downwardly extending front and back portions, said front portion terminating in a concave, substantially semi-circular lower edge and said back portion being of substantially greater length than said front portion and extending downwardly to join said crotch portion in the rear crotch area of the wearer, and said crotch portion comprising a crotch member formed separately

from said trunk member and comprising an elongate section of material, one end of which is substantially V-shaped and is symmetrical about the center line of said crotch member, said V-shaped end of said crotch member lying just above said semi-circular edge of said trunk member and being selectively sewed to the outside of said trunk member at spaced points therealong to form a fly opening.

2. A garment in accordance with claim 1 wherein said trunk member is formed directly from a tubular length of material.

3. A garment in accordance with claim 1 further comprising a pair of binding strips framing said leg openings, said binding strips each comprising an elongate fabric strip folded along the length thereof to produce an inner and outer layer, said inner layer being further folded to produce a double layer, an elongate elastic strip disposed between said double layer, and a double stitching arrangement for joining the binding strip to the portion of the garment forming said leg openings and capturing said elastic strip therebetween.
